UNITED STATES PATENT OFFICE.

LEE D. CRAIG, OF SAN FRANCISCO, CALIFORNIA.

ERASING-SHIELD FOR TYPE-WRITERS.

SPECIFICATION forming part of Letters Patent No. 394,342, dated December 11, 1888.

Application filed April 24, 1888. Serial No. 271,690. (No model.)

To all whom it may concern:

Be it known that I, LEE D. CRAIG, of San Francisco, in the county of San Francisco and State of California, have invented a new and 5 useful Improvement in Erasing-Shields for Type-Writers; and I do hereby declare that the following is a full, clear, and exact description of the same.

Every type-writer operator is aware of the 10 difficulty experienced in erasing words or letters from a page of type-written matter, owing to the great liability there is of erasing or blurring letters or words contiguous to those which it is desired to obliterate, thus 15 spoiling the appearance of the sheet. Extreme care, therefore, is required in the operation of erasing, and a consequent loss of time entailed upon the operator.

It is the object of my invention to provide 20 a device for use in the erasure of words or letters, which can be so adjusted as to shield all the letters except those which it is desired to erase, so that all blurring will be avoided, and which can be placed in position 25 for use so speedily that a minimum amount of time will be lost.

My invention therefore consists, primarily, 30 of a rectangular plate having a longitudinal opening therein of any suitable dimensions, and a slide adjustable on said plate, so as to 35 cover as much of the longitudinal slot as is desirable.

The invention consists, secondly, of a rectangular plate having a longitudinal opening 35 therein, a sliding plate adapted to cover said opening, said sliding plate having a tongue fitted to the opening in the main plate and adapted to act as a guide for the eraser.

My invention is illustrated in the accompanying drawings, in which Figure 1 represents a perspective view of my invention, and Fig. 2 a longitudinal section.

While I have designed my invention particularly for use in connection with type-writers, nevertheless it will be readily understood that it can be used in connection with the erasing of words or letters from manuscript.

In the drawings, A is a rectangular plate 50 stamped out of sheet metal, preferably nickel-plated, and may be of any suitable length and width; but in practice I make it about one-half as long as the carriage of a type-writer, and in width about equal to three or

four times the space ordinarily left between 55 the lines in type-written matter. These dimensions are, however, not material, but have been found convenient. This plate is bent over at the sides, forming ways a, in which a plate, B, hereinafter described, is adapted to 60 slide. The plate A has a central longitudinal opening, b, formed in it extending nearly its whole length, said opening being of such width that when the opening in the plate A is positioned over the line of type-writing 65 containing the character to be erased the lines immediately above and below will be entirely shielded.

Fitted to slide in the ways a is a plate, B, made of any suitable material, and this plate 70 B is adjustable on the plate A in order to make the length of the opening b greater or less according to the size of the erasure to be made. This plate B is preferably made with a tongue, c, formed upon one end, this tongue 75 being inclined slightly downward and of such width as to snugly fit the longitudinal opening b in the plate A, thus acting as a guide for the erasing-tool, and, as this tongue has a knife-edge at its extremity, it will be 80 seen that the erasing-tool in its movement will not be retarded by binding against the end of the tongue, for the knife-edge will offer no obstruction to its passage, but allow it to slide easily from the paper upon the incline.

I claim—

1. A shield for use in erasing words or letters, consisting of a plate, A, having an opening therein for disclosing the character to be 90 erased, and a sliding plate adjustable on said plate A, adapted to close the opening therein, substantially as described.

2. A shield for use in erasing words or letters, consisting of a plate, A, having the opening therein for disclosing the character to be 95 erased, and a sliding plate, adjustable on said plate A, adapted to close the opening therein, having a tongue for guiding the eraser, substantially as described.

In testimony whereof I have signed my name to this specification in the presence of two subscribing witnesses.

LEE D. CRAIG.
